Patented Sept. 22, 1970

218,768

RIDING-TYPE POWER LAWN MOWER

Viktor Schreckengost, Cleveland Heights, Ohio, assignor
to The Murray Ohio Manufacturing Co., Nashville,
Tenn., a corporation of Ohio

Filed Sept. 10, 1969, Ser. No. 19,083

Term of patent 14 years

Int. Cl. D8—01

U.S. Cl. D40—1

Des. 218,768

PAGE 2

Fig. 3

FIG. 5

Fig. 6

FIG. 1 is a perspective view of a riding-type power lawn mower;

FIG. 2 is a top plan view thereof;

FIG. 3 is an elevational view of the side opposite that shown in FIG. 1;

FIG. 4 is an elevational view of the side opposite that illustrated in FIG. 3;

FIG. 5 is a front elevational view; and

FIG. 6 is a rear elevational view.

I claim:

The ornamental design for a riding-type power lawn mower, substantially as shown.
